MOTOR-CONTROL SYSTEM.

1,425,640.

Specification of Letters Patent. Patented Aug. 15, 1922.

Application filed January 29, 1917. Serial No. 145,268.

To all whom it may concern:

Be it known that I, ADOLEH A. GAZDA, a citizen of the United States, and a resident of Wilkinsburg, in the county of Allegheny 5 and State of Pennsylvania, have invented a new and useful Improvement in Motor-Control Systems, of which the following is a specification.

My invention relates to motor-control systems and particularly to such systems as embody induction motors and speed-controlling means therefor.

My invention has for its object to provide a system of the above-indicated character 15 that shall be simple and inexpensive in construction and efficient in operation to effect the acceleration of an induction motor in a smooth and uniform manner and with a minimum degree of unbalancing of the currents traversing the several phase-windings.

Numerous methods have been proposed heretofore for effecting the acceleration of induction motors having phase-wound secondary members and external resistors connected in circuit with the several phase-windings. One of such methods consists in successively shunting like portions of each of the several resistors and repeating this 25 operation until the resistors are entirely shunted. This method requires a relatively large number of switches, since a separate switch is required for each resistor section. It has been found, in practice, also, that excessive currents traverse the secondary winding and sudden increases in torque occur at 30 the successive steps of the latter portion of the acceleration of the motor.

A second method consists in simultaneously shunting like portions of two resistors 40 in a three-phase circuit and then shunting an equal portion of the third resistor. This method requires a comparatively large number of switches and, in addition, results in a greater unbalancing of the currents traversing the several phase-windings than is desirable. These unbalanced conditions 45 result from the fact that the shunted portions of the two resistors are in parallel relation to each other, whereas, the corresponding section of the third resistor is in series with its respective phase-winding. The resistance of one phase is thus materially higher than that of the other two phases.

I provide an arrangement in which the 55 phase-windings of an induction motor and

the resistors in circuit therewith are arranged in star-connection. A series of switches or contact members, which may be controlled in any suitable manner, operate to successively shunt a portion of one of the resistors and to simultaneously connect substantially equal portions of the other resistors in a loop circuit. This process continues until the resistors are entirely shunted.

This arrangement possesses the advantage 65 that the number of switches required is smaller than that for either of the systems referred to above. It has been found, in practice, that the acceleration of the motor may be accomplished in a manner that is 70 more smooth and uniform than is possible by either of the methods of the prior art. The increases in torque are uniform throughout the operation of acceleration and the unbalancing of the secondary currents is of 75 minimum degree.

These conditions obtain because the resistor, of which the first section to be shunted is a part, is, upon the shunting of the first section, of lower value than the other two 80 resistors which are in parallel relation to each other. The effective resistances of the several phase circuits are thus maintained more nearly equal than is the case in either of the methods previously described.

In the accompanying drawing, Fig. 1 is a diagrammatic view of circuits and apparatus embodying my invention. Fig. 2 is a diagrammatic view of the circuits for controlling the switches embodied in the system 90 of Fig. 1.

Referring particularly to Fig. 1, line conductors 1, 2 and 3, which may be connected to any suitable source of three-phase alternating current, supply energy to an induction motor 4 having a phase-wound secondary member. The secondary winding of the motor is connected, through the usual slip rings, to external resistors 5, 6 and 7. The resistors are controlled by electromagnetic 95 switches 8, 9, 10, 11, 12, 13 and 14.

Reference may now be had to Fig. 2 in which is illustrated an arrangement for controlling the circuits of the actuating coils of the several electromagnetic switches. For 105 convenience, the several coils are designated by the same reference numerals as are employed to designate the corresponding switches. A controlling mechanism 15 is provided with a series of contact segments 110

16 which successively engage a series of contact fingers 17 to energize the circuits of the actuating coils.

To start the motor, the controller 15 is actuated to the left, as viewed in Fig. 2, to complete the circuit of the actuating coil of switch 8. The latter then closes to shunt a section of resistor 7. The resistance of each of the circuits of the secondary winding is reduced since each phase-winding is in series with the parallel paths of the other phase-windings. The unbalance produced by the shunting of the section of resistor 7 is not pronounced because the corresponding sections of resistors 5 and 6 are in parallel relation to each other and in series relation to the resistor 7 which has been reduced.

In the second position of the controller 15, the circuit of the actuating coil of switch 9 is closed and the latter operates to complete a connection for the terminals of sections of resistors 5 and 6 which correspond in arrangement and substantially in value, to the section of resistor 7 that is controlled by switch 8. The resistances of the several circuits of the phase-windings are again reduced by the shunt circuit thus established.

The sections of resistors controlled by the switch 9 are not entirely removed from the circuits of all of the phase-windings, as will be readily understood. The sections of resistors 5 and 6 connected in a loop circuit by the switch 9 are in parallel relation to each other with respect to circuits comprising the resistor 7 and are shunted with regard to the circuit comprising the resistors 5 and 6 and the corresponding phase-windings. This arrangement produces the minimum degree of unbalanced resistance in the secondary circuits without actually shunting equal portions of each of the several resistors.

In a similar manner, the switch 10 operates to shunt a second section of resistor 7 and the switch 11 operates to shunt substantially equal portions of the resistors 5 and 6. The conditions obtaining at these steps correspond to those caused by the closing of switches 8 and 9, respectively. Similar conditions obtain, also, upon the respective closing of switches 12 and 13. The closing of switch 14 completes a shunt circuit for the entire resistors.

It will be noted that only seven switches are required to effect the acceleration of the motor. A corresponding number of steps of acceleration are provided. In the first arrangement of the prior art to be described, at least nine switches are required to effect the shunting of resistors having like numbers of sections and, in addition, the acceleration is not smooth and gradual as in the applicant's arrangement. In the second arrangement, it is necessary to employ eight switches to accomplish similar results and the unbalance of currents in the several

phase-windings is greater than that obtainable in the system arranged according to my invention.

While I have shown and described a three-phase alternating-current system, it will be understood that such arrangement is shown by way of example only and that my arrangement is adapted equally well for use in connection with systems of any desired number of phases.

75

I claim as my invention:

1. In a motor-control system, the combination with an alternating-current motor having a plural-phase winding and resistors in circuit therewith, of means for successively shunting a portion of one of said resistors and simultaneously connecting portions of other of said resistors in parallel relation to each other and in series relation to said one resistor.

80

2. In a motor-control system, the combination with an alternating-current motor having a secondary winding and resistors in circuit therewith, of means for successively shunting a portion of one of said resistors and connecting portions of other of said resistors in a loop circuit.

85

3. In a motor-control system, the combination with an alternating-current motor having a three-phase secondary winding and resistors in circuit therewith, of means for successively shunting a portion of one of said resistors and simultaneously connecting portions of the other resistors in parallel relation to each other.

90

4. The method of accelerating an alternating-current motor which consists in successively reducing the resistance in circuit with one phase section of one of the motor windings and then simultaneously reducing the resistance in circuit with other phase sections of the motor winding and increasing the resistance in circuit with said one phase section.

105

5. The method of accelerating an alternating-current motor which consists in successively shunting a portion of a resistor in circuit with one phase section of the motor windings and then connecting corresponding portions of the other resistors in a loop circuit.

110

6. The method of accelerating an alternating-current motor which consists in first reducing the resistance in circuit with one phase section of one of the motor windings and then reducing the resistance in the other phase sections of said motor winding and increasing the resistance in said first phase section.

120

7. The method of accelerating an alternating-current motor which consists in first short-circuiting a portion of the resistance in circuit with one phase section of one of the motor windings and then short-circuiting portions of the resistance in circuit

125

130

with the other phase sections of said motor winding and inserting said last-named portions in said first-named phase section.

8. The method of accelerating an alternating-current motor which consists in reducing the resistance in circuit with one of the phase sections, simultaneously reducing the resistance in circuit with a plurality of the other phase sections and increasing the 10 resistance of said one-phase circuit and then repeating the operations in order.
9. The combination with an alternating-

current motor having a secondary winding and a resistor in each phase circuit of said winding, of means for successively shunting 15 a portion of one of said resistors and connecting substantially equal portions of the other resistors in a loop circuit and then repeating the operations in the order named.

In testimony whereof, I have hereunto 20 subscribed my name this 20th day of January, 1917.

ADOLPH A. GAZDA.
